Atty.

UNITED STATES PATENT OFFICE.

JAMES W. McINDOE, OF MEDFORD, MASSACHUSETTS, ASSIGNOR OF ONE-HALF TO
ARTHUR E. WHITNEY, OF WINCHESTER, MASSACHUSETTS.

BOARD.

1,180,516.

Specification of Letters Patent. Patented Apr. 25, 1916.

Application filed March 30, 1915. Serial No. 18,613.

To all whom it may concern:

Be it known that I, JAMES W. McINDOE, a citizen of the United States of America, and a resident of Medford, in the county of 5 Middlesex and State of Massachusetts, have invented certain new and useful Improvements in Boards, of which the following is a specification.

This invention relates to boards to be used 10 in the inside finish of a building, the manufacture of furniture, and various other purposes, and has for its object the provision of a material of this character which may be used as a substitute for high priced wood 15 now used for such purposes.

The invention consists in a board which has indented into one surface the exact reproduction of the grain of wood the indentations of which are adapted to be filled 20 with a material of a different shade from the body portion of said surface.

The invention further consists in certain novel features of construction and arrangement of parts which will be fully understood by reference to the description of the 25 drawings and to the claims hereinafter given.

Of the drawings: Figure 1 represents an elevation of a portion of a board embodying 30 the principles of the present invention. Fig. 2 represents a section of the same on an enlarged scale. Fig. 3 represents a similar view showing one surface thereof provided with a plurality of indentations. Fig. 4 35 represents a similar view showing the indentations filled, and Fig. 5 represents a section of a portion of the same, the cutting plane being on line 5—5 on Fig. 4.

Similar characters designate like parts 40 throughout the several figures of the drawings.

In the drawings, 10 is a layer of fiber board or similar material having secured to opposite faces thereof the layers of paper 11 45 and 12. The paper facing 11 is provided with a plurality of indentations 13 which are made in the facing 11 without breaking the material, the facing used being sufficiently tough to prevent the material being 50 separated when the indentations 13 are formed therein. When these indentations 13 are formed in the facing 11 they will be forced into the fiber board as indicated in Fig. 4, the fiber board 10 being sufficiently 55 soft to permit the embedding of the in-

dentations 13 therein. These indentations 13 are arranged in such a manner as to form a design exactly representing the grain of wood, some of the indentations being deeper than others and each indentation 13 being 60 deeper at one point than at its ends as indicated in Fig. 5 of the drawing.

The indentations 13 are formed in the facing 11 by means of a new and improved process in which the exact reproduction of 65 the grain of any wood may be transferred to the board and indented therein with all the variations in outline and depth that occur in the wood itself when the gum has been removed from the grain. 70

When the indentations 13 have been formed in the facing 11 of the pulp board they are filled with a coloring matter 14 of a different shade from the body of said facing 11, this coloring matter bringing out 75 every irregularity in the indentations 13 and causing the grain to stand out in marked contrast with the remaining portion of said paper facing. Owing to the fact that in the manufacture of the wall board the indentations 13 are formed without breaking through the paper facing 11, it is impossible for the coloring matter to leak through into the intermediate fiber board 10. The coloring matter used in filling the indentations 80 is such as will become hardened when it becomes dry, and the outer face thereof will be flush with the outer surface of the paper facing 11.

The paper facing 11 is of such a character 90 as will freely take color without injury thereto and when the board is ready for use any color may be applied thereto and its surface may be treated in any other manner that wood might be treated. Varnish may 95 be applied if desired or the whole surface polished. When thus treated it is impossible to distinguish this wall board from the wood of which it is a counterpart. It is obvious that both faces may be indented when the 100 board is to be used for particular purposes.

In the process of manufacture of the board there is absolutely no hand work in the shaping of the indentations forming the grain, such indentations being the exact 105 reproduction of the grain in the natural wood.

It is believed that the many advantages of this invention will be fully understood from the foregoing description. 110

Having thus described my invention, I claim:

1. As a new article of manufacture, a board of pulp provided with a facing of tough paper having therein a plurality of indentations representing the grain of wood. 40
2. As a new article of manufacture, a board having a paper facing and said facing having therein a plurality of indentations 45 representing the grain of wood, the indentations being filled with a material differing in shade from the body of said paper facing.
3. As a new article of manufacture, a board having a paper facing and said facing having therein a plurality of indentations representing the grain of wood, the indentations being filled with a material differing in shade from the body of said paper facing, and extending to the surface of said 50 paper.
4. As a new article of manufacture, a board of fiber having a facing of tough paper provided with a plurality of indentations forcing said facing into the fiber without breaking. 55
5. As a new article of manufacture, a board of fiber having a paper facing provided with a plurality of indentations forcing said facing into the fiber without breaking, said indentations being filled with a material of a different shade from the body of said paper facing. 60
6. As a new article of manufacture, a board of fiber having a paper facing provided with a plurality of indentations forcing said facing into the fiber without breaking. 65

ing, said indentations being filled with a material of a different shade from the body of said paper facing, and extending to the surface of said paper facing.

7. As a new article of manufacture, a board of paper pulp having a facing of paper provided with a plurality of indentations representing the grain of wood, the walls of said indentations being formed of 45 said paper facing embedded in said pulp.

8. As a new article of manufacture, a board of paper pulp having a facing of tough paper provided with a design indented into said facing. 50

9. As a new article of manufacture, a board having a paper facing provided with a design indented into said facing with said design filled with a material of a different shade from the body of the board. 55

10. As a new article of manufacture, a board having a paper facing provided with a design indented into said facing, with said design filled with a material of a different shade from the body of the board, and extending to the surface of said board. 60

11. As a new article of manufacture, a board having two layers of paper with pulp board interposed between them and a design formed in one or both layers of paper embedding portions thereof in the pulp board. 65

Signed by me at Boston, Mass., this 26th day of March, 1915.

JAMES W. McINDOE.
